UNITED STATES PATENT OFFICE.

WILLIAM L. JUHRING, OF BROOKLYN, NEW YORK.

DESIGN FOR A BOTTLE.

SPECIFICATION forming part of Design No. 23,352, dated June 12, 1894.

Application filed May 18, 1894. Serial No. 511,487. Term of patent 7 years.

To all whom it may concern:

Be it known that I, WILLIAM L. JUHRING, a citizen of the United States, residing in the city of Brooklyn, county of Kings, and State of New York, have invented and produced a new and original Design for Bottles, of which the following is a specification.

In the drawings Figure 1, is an elevation of my design, and Fig. 2, is a section through the same.

The leading feature of my design consists of a bottle having its body periphery formed of a projecting band at top and bottom with a depressed portion between, the neck being of ordinary shape.

In the drawings the neck of the bottle is shown at *a*, the center of the body at *b* and the projecting, top and bottom portions at *c d*, these parts presenting a concave face rounding to the body proper at the edges as clearly shown in the sectional view. 20

I claim—

The design for a bottle herein shown and described.

In testimony whereof I affix my signature in presence of two witnesses. 25

WILLIAM L. JUHRING.

Witnesses:

J. ROBERT FENTON,
F. J. DESSOW.
